CLAIM

The ornamental design for a display screen or portion thereof with graphical user interface, as shown and described.

DESCRIPTION

FIG. 1 is a front view of a first embodiment of a display screen or portion thereof with graphical user interface.

FIG. 2 is a front view of a second embodiment of the display screen or portion thereof with graphical user interface shown in FIG. 1; and,

FIG. 3 is a perspective view of FIG. 1, but shown with additional broken line subject matter.

The broken line showing of an electronic device and display screen illustrate environmental structure and the article of manufacture, respectively. The broken line showing of the centralized microphone icons and all concentric semi-circles illustrate portions of the graphical user interface. The broken line showing of a person in FIG. 3 illustrates environment. None of the broken lines form part of the claimed design.
